UNITED STATES PATENT OFFICE.

WILLIAM MEIER, OF NEW YORK, N. Y.

PEDAL-CONTROL LIQUID MIXER.

1,418,193.

Specification of Letters Patent. Patented May 30, 1922.

Application filed October 25, 1919. Serial No. 333,151.

To all whom it may concern:

Be it known that I, WILLIAM MEIER, a citizen of the United States, and a resident of New York, in the county of New York and State of New York, have invented a new and Improved Pedal-Control Liquid Mixer, of which the following is a full, clear, and exact description.

This invention relates generally to a liquid mixing means, and more particularly to an improved device for mixing hot and cold water, which means may be controlled by a foot pedal whereby hot and cold water may be readily mixed in proper proportions to obtain and maintain a desired temperature.

A device of this character is particularly adapted for use by dentists and others, who, while working with their hands, may desire to control the flow and temperature of the water without the necessity of interrupting the work in hand. This may be readily accomplished by the use of a pedal control liquid mixer. Further, a device of this character is particularly adapted for use under sanitary conditions, where it is desired to control the flow and temperature of water, without the use of the hands.

One of the objects of this invention is to provide in a liquid mixer, a means of simple and compact construction whereby the temperature and flow of a liquid may be controlled by a pedal which may be actuated by the foot.

A further object of this invention is to provide in a hot and cold water mixer, a construction which will permit the mechanism of the mixer to be actuated by the foot, and held in any predetermined position whereby a desired temperature is obtained, without the necessity of having to hold the foot on the actuating mechanism.

Still a further object of this invention is to provide in a pedal-actuated device for controlling the temperature of a hot and cold water mixer, a simple and compact construction which will permit the water flow to be readily shut off without having to use the hands.

With the above and other objects in view, the invention consists in the construction, arrangement and combination of parts hereinafter more fully described, and more particularly set forth in the appended claims.

In the drawings, showing for example a

practical embodiment of the invention, similar characters of reference designate corresponding parts in the several views.

Figure 1 is a longitudinal sectional view showing certain parts in elevation, looking in the direction of the arrows and taken on the line 1—1 of Figure 2.

Figure 2 is an elevation view, partly broken away, showing more clearly the construction of the pedal mechanism for controlling the movement of the liquid mixer.

Figure 3 is a broken sectional view looking in the direction of the arrows and taken on the line 3—3 of Figure 2.

In the drawings, showing, for example, one of the practical embodiments of the invention, the pedal-control mechanism comprises a plurality of relatively movable members 10 and 11, one of which, 10, for example, having a toothed or ratchet surface 12 thereon. One end 13 of the member 10 is pivotally connected in any suitable manner to a support, which in the form shown is the base 14 of a water mixer hereinafter more fully described. The other relatively movable member 11 is held in sliding engagement with the toothed member 10, a pawl 15 being arranged upon the member 11 so as to engage the teeth 12, a spring 16 being provided to normally hold the pawl in yielding engagement with the toothed surface.

Fixed to the member 11 and extending outwardly therefrom, is a pedal 17, which is adapted to receive the foot in order to cause relative movement between the members 10 and 11. With reference to Figs. 2 and 3, the pawl 15 is carried on a pin 18 which is rotatably supported in a bracket 19, fixed to the foot pedal 17, and extends laterally thereof. One end of the pin extends outwardly from the pedal and a supplemental pedal 20 is fixed thereto, the end of said pedal 20 being so arranged as to be normally above the foot pedal 17. It is thus seen that if it is desired to move the foot pedal 17 downward, the foot is placed thereon and the pedal is pressed downward to the desired position, in which position the members will be held by engagement of the spring-pressed pawl 15 with the toothed surface 12.

In the form shown in Fig. 2, the member 11 is tubular in form and fits over or telescopes the member 10, an opening 21 being

provided in order that the pawl 15 may contact with the toothed surface 12. The upper end of the member 11 is pivotally connected to one end of a link member 22, by a pin 23, 5 or other suitable means, the other end of the link member being pivotally connected in any suitable manner to a fixed support, shown in the drawings as a bracket 24, mounted on a cap 25 of the liquid mixer. 10 Connecting the cap 25 and the base 14 and interposed therebetween, is a body 26, which may be of any suitable form, but is shown in the drawings as comprising a tubular casing having a threaded connection at its upper 15 end to receive the cap 25, and a threaded connection at its lower end to receive the base 14. The body 26 is provided with inlet openings 27 and 28, to receive hot and cold water inlet pipes 29 and 30, respectively. The body 26 is also provided with another opening 31 to receive an outlet pipe 32.

As a means of controlling the flow of water through the hot and cold inlet pipes, gate valves 33 and 34, respectively, are provided. 25 The said gates may be provided with suitable washers 35 and 36, to form a seat for the inlet pipes 29 and 30, respectively. In the form shown, the gates 33 and 34 are pivotally connected at one end thereof by a pin 30 connection 37, to the base 14. As a means of controlling the movement of the gates 33 and 34 to effect the proper mixing of the hot and cold water in order that the temperature of the water flowing from the outlet may be 35 controlled, a cam or inclined surface is formed at one side of each of the gates, and a gate-actuating member 38, mounted on a spindle 39, is arranged to move between the said gates in order to obtain proper movement thereof.

In order to first obtain cold water and to gradually arrange the control so as to increase the temperature of the water until only the hot water is obtained, the gate 34 45 controlling the cold water is provided with a V-shaped surface 40, and that portion of the gate 33 corresponding to the upper portion of the V-shaped surface on the gate 34 is substantially parallel to the axis of the spindle 39, so that as the gate-actuating member 38 is moved downward to the pin 41, the gate 33 will remain seated, and the gate 34 will open, thus permitting the cold water to flow. Further downward movement of the gate-actuating member 38 will gradually close the gate 34, and, at the same time, permit the gate 33 to be unseated from the hot water inlet, the latter movement being effected by providing an inclined surface 42 50 on one side of the gate 33. When the lowermost point 43 is reached by the gate-actuating member 38, the gate 34 will again be seated and the gate 33 will be unseated, thus permitting a full flow of hot water. In order to maintain the gate-actuating member 60

in proper relative position and to guide the spindle 39, a guide stem 44 is fixed in a boss 45 of the base 14, the upper end of the stem fitting within the lower end of the spindle 39. The upper end 46 of the spindle extends outwardly of the water-mixing device 70 and is guided through a suitable bearing 47 and packing gland 48 of the cap 25.

As a means of normally maintaining the gates in a seated position, a spring 49 is interposed between the base and the lower end of the spindle 39, one end of said spring being seated on the boss 45 and the other end on a collar 50 at the lower end of the spindle 39. By such an arrangement, in order 75 to effect a mixing of the liquids, it is only necessary to exert a downward force upon the spindle, to compress the spring 49, and as soon as the force is withdrawn, the gates will again automatically be reseated. It is 80 to be understood that the invention is not to be limited to the water-mixing means shown herein, but is adapted to be used in connection with any water-mixing devices having a hot and cold water supply in which 85 a plurality of gates or valves are controlled by a spring-pressed spindle having a gate-actuating member thereon.

As a means of communicating the movement of the foot pedal 17 to the spindle 39, 95 the upper end 46 of the spindle is connected in a suitable manner to the link 22. In the form shown, the upper end 46 of the spindle 39 is forked, and is provided with a pin 51, which is guided in a slot 52 in the link 22. 100 It is thus seen that when the foot pedal 17 is depressed, the link 22 is moved about its point of support, which movement in turn causes the spindle 39 to be moved downward carrying therewith the gate-actuating member 38, which in turn controls the movement 105 of the gates 33 and 34.

After the foot pedal has been depressed the necessary distance in order to obtain the proper mixing of the liquids to the desired temperature, the foot may be removed from the pedal and the latter will be held in such a position by the engagement of the pedal with the toothed surface 12. If it is desired to shut off the water supply, it is only 110 necessary to place the foot upon the supplemental pedal 20, which will disengage the pawl 15 from the toothed surface 12, when the spring 49 will force the spindle 39 upward carrying the gate-actuating member 38 115 therewith, and the gates will again be seated.

It is to be understood that while one practical embodiment of the invention has been shown herein, various changes and modifications may be made thereof without departing from the spirit and scope of this invention.

I claim:

1. In a device of the character described 120

comprising hot and cold water inlets, valve gates therefor, each of said gates having an inclined surface thereon, a spring-pressed spindle, a gate-actuating member mounted on said spindle and arranged to successively actuate said gates, a means connecting to said spindle including a pedal, a pawl associated therewith, and a relatively movable toothed member adapted to cooperate with said pawl, whereby the said gate actuating member may be controlled by movement of said foot pedal.

2. In a liquid mixer comprising a casing having hot and cold water inlets therein, valve gates for said inlets, each of said valve gates having an inclined surface thereon, a gate control member, and a spring pressed spindle connected to said gate control member, one end of said spindle extending outward of the casing, a mechanism connected with the spindle and adapted to be actuated by the foot to control the movement of the said gates, whereby the temperature of the liquid may be regulated.

3. In a liquid mixer comprising a casing having hot and cold water inlets therein, valve gates for said inlets, each of said valve gates having an inclined surface thereon, a gate control member, and a spring pressed spindle connected to said gate control member, one end of said spindle extending outward of the casing, a mechanism connected with the spindle and adapted to be actuated by the foot to control the movement of the said gates and to hold the same in any predetermined position.

4. In a hot and cold water mixer including a casing and a spring pressed spindle having

one end thereof extending outward of said casing, a foot control mechanism comprising a foot pedal, a toothed ratchet member pivotally mounted, a means for holding said ratchet member in sliding engagement with said pedal, a spring pressed pawl mounted on said pedal, and adapted to engage said ratchet, and a means connecting the pedal and the spindle, whereby the said spindle may be actuated by pressing the pedal.

5. In a hot and cold water mixer including a casing, and a spring pressed spindle having one end extending from said casing, a foot control means for controlling the movement of said spindle, and a means for holding said last named means in a predetermined actuated position.

6. In a hot and cold water mixer including a casing, and a spring pressed spindle having one end extending from said casing, a foot control means for controlling the movement of said spindle, and a means for holding said last named means in a predetermined position, the said foot control means including a foot pedal, a vertically extending member pivotally mounted, another vertically extending member connected to the pedal, and adapted to telescope said pivoted member, and a link having one end thereof pivotally mounted at a fixed support, and the other end thereof connected to the second named telescoping member, the said link member having a connection with the spindle whereby when the foot pedal is pressed, the said spindle will be actuated.

WILLIAM MEIER.
